UNITED STATES PATENT OFFICE.

CLAUDE E. MENTZER, OF DES MOINES, IOWA.

SCENERY STOP-IRON.

1,161,000.

Specification of Letters Patent. Patented Nov. 16, 1915.

Application filed March 16, 1915. Serial No. 14,833.

To all whom it may concern:

Be it known that I, CLAUDE E. MENTZER, a citizen of the United States, and resident of Des Moines, in the county of Polk and State of Iowa, have invented a certain new and useful Scenery Stop-Iron, of which the following is a specification.

The object of my invention is to provide a scenery stop iron of extremely simple, durable and inexpensive construction, capable of being readily and easily secured to the stiles of scenery and rigidly connected when they are lashed together.

A further object is to provide a scenery stop iron of the kind mentioned, which can be readily and easily adapted for use in securing the scenery sections in different positions.

A further object is to provide such a device so arranged that when the scenery is taken down for transportation, the stop iron members will project a minimum distance from the stiles.

Still a further object is to provide a scenery stop iron having coacting parts, one part being adapted to be secured to the stile of the scenery and to project a minimum distance therefrom, the other part being capable of having a variety of forms, any of which may be arranged to coact with the part secured to the scenery.

My invention consists in the construction, arrangement and combination of the various parts of the device, whereby the objects contemplated are attained, as herein-after more fully set forth, pointed out in my claim and illustrated in the accompanying drawings, in which:

Figure 1 shows a rear elevation of two sections of scenery affixed with a stop iron embodying my invention. Fig. 2 shows a vertical, sectional view taken on the line 2—2 of Fig. 1, the dotted lines illustrating one way in which the stop iron may be used. Fig. 3 shows a horizontal, sectional view of a slightly modified form of the removable stop iron member. Fig. 4 shows a similar view of another form. Fig. 5 shows a perspective view of the form of the stop iron illustrated in Figs. 1 and 2.

In the forms of my invention illustrated in the accompanying drawings, I have used the reference numeral 10 to indicate generally sections of scenery for use in theaters and the like, having the upright rigid stile

members 11, which are ordinarily made of wood.

It is well known that the stile members of adjacent sections in various settings must be set in horizontal alinement at right angles to each other, at acute angles to each other, etc., and that one of the problems of setting scenery is to securely and quickly connect the adjacent sections together. This object could be accomplished much more easily were it not for the fact that it is not desirable to have parts on the stiles which project to any considerable distance away from such stiles. For accomplishing the objects hereinbefore set forth, therefore, I have devised the scenery stop irons which really compose two parts, namely a member adapted to be secure to the stile and members of different forms adapted to coact with the permanently affixed member.

The member which is affixed to the stile comprises a flat portion 12 which may be secured to the stile in any suitable way, as by bolts. On the upper portion of the part 12 is an upwardly extending part 14 having a shoulder 15 at its lower end adjacent to the part 12, and having this upper portion spaced from the stile 11. I preferably use two of the permanently affixed members on each stile of each section of scenery.

The coacting stop iron comprises a flat horizontal member 16, adapted to rest against the stile and to be slid downwardly between the stile and the portion 14, as illustrated in all of the figures. At one end of the member 16 is a right angled extension 17 designed to engage the side of the stile, as illustrated. This end I shall, for convenience, call the inner end of the member 16. The outer end of the member 16 may have various shapes for accommodating the stop irons for setting the scenery sections in different positions.

In Figs. 1, 2 and 5 I have shown the member 16 with a vertical, rearwardly extending rib 18 adjacent to the member 14 on the side thereof opposite the extension 17, and beyond the rib 18 is a portion 16^a which extends beyond the side edge of the stile 11 on which the member 12 is mounted. When two scenery sections are arranged in horizontal alinement, the stile 11 of the section adjacent to the section having the stile 11 to which the member 12 is secured, is placed edge to edge or side to side with the

stile on which said member 12 is secured, as illustrated in Fig. 2, and is overlapped by the portion 16^a, as shown in Figs. 1 and 2. The sections are then lashed together as desired. The rib 18 and the extension 17 prevent horizontal sliding movement of the member 16. It will, of course, be readily seen that the member 16 may be quickly and easily removed when the scenery is taken down.

It will be seen that the form of the device shown in Figs. 1, 2 and 5 may be employed where the second scenery section is placed with its stile at right angles to the stile to which the member 12 is secured, as illustrated by the dotted lines in Fig. 2.

In Fig. 3 I have shown a slightly modified form of the member 16 having at its end opposite the extension 17 a right angled extension 19 extending in the opposite direction from the extension 17, and adapted to engage the member 14 to prevent longitudinal movement of the member 16 with relation to said member 14, and also to engage the stile 11 of the adjacent section of scenery extending rearwardly from the section on which the member 12 is mounted at right angles thereto.

In Fig. 4 is another modified form of the member 16 having on its end opposite the extension 17 a parallel extension 20 at the end of which is a right angled extension 21 extending away from the extension 20 in a plane parallel with that in which the member 16 rests.

It will be understood that some changes may be made in the arrangement and con-

struction of the parts of my improved stop irons, and it is my intention to cover by this application any such changes which may be included within the scope of my claim.

My improved stop iron is adapted to be so constructed that the part permanently affixed to the stile shall extend away from the stile as little as possible, and yet be adapted to firmly secure the detachable member to the stile. The other portion is adapted to be so constructed as to be gripped between the member 14 and the stile and to be held against longitudinal movement, and at the same time have a portion adapted to engage the stile of the adjacent section.

I claim as my invention:

In a device of the class described, a flat member adapted to be secured to a stile, an upwardly extending portion on said flat member having a shoulder at its lower end, and being adapted to be spaced from the stile, a coacting member adapted to be received between the stile and the spaced member and having the right angled extension at its inner end adapted to engage the edge of the stile, and having at its other end means for preventing longitudinal movement in one direction, and means for engaging the stile of an adjacent scenery section.

Des Moines, Iowa, March 1, 1915.

CLAUDE E. MENTZER.
